(No Model.)

C. C. CARPENTER.

BUSTLE.

No. 334,638.

Patented Jan. 19, 1886.

UNITED STATES PATENT OFFICE.

CHARLES CLARENCE CARPENTER, OF NEW YORK, N. Y.

BUSTLE.

SPECIFICATION forming part of Letters Patent No. 334,638, dated January 19, 1886.

Application filed September 18, 1885. Serial No. 177,421. (No model.)

To all whom it may concern:

Be it known that I, CHARLES C. CARPENTER, a citizen of the United States, residing at New York city, in the county of New York and State of New York, have invented certain new and useful Improvements in Bustles; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to bustles; and the novelty consists in the construction, arrangement, and adaptation of parts, as will be more fully hereinafter set forth, and specifically pointed out in the claims.

20 Bustles formed with horizontal stuffed pockets are well known, and it has been a fault with such that they break down in the rear central line, owing, possibly, to the weight of the drapery. Among other features which in

25 such bustles have impaired their durability is the fact that the unsupported edges have, by wear, doubled the material upon itself until the greater portion would ride up out of proper place, thus defeating the purpose for which

30 the article was designed, and in any event losing the graceful contour desired. I seek to obviate these and other difficulties.

I arrange the filled tubes or pockets with their centers upon a higher plane than their ends, thus arching the said pockets and increasing their resisting-power without adding to the weight or bulk of the structure. I bind the ends of the pockets forcibly together upon either side, whereby the expanding force of

40 the material in the pockets, near such ends, serves with a constant force to hold the back of the bustle down to the limit of the fabric. I arrange a strengthening-spring in the lacing-plates adjacent to their junction with the ends of the pockets, which spring acts upon either side to keep the edge of the bustle straight and prevents the doubling and consequent breaking.

The feature of arching the rolls or pockets

55 be readily understood, and is of importance in my device.

The invention is illustrated in the accompanying drawings, which form a part of this specification, and in which—

Figure 1 is a side elevation, and Fig. 2 an inner face view. Fig. 3 is a plan view on a smaller scale, showing the manner of stitching the fabric to arch the pockets.

Referring to the drawings, A designates the sheets of fabric, which, by curved rows of stitching *a*, forms pockets *b*, which in the completed article are stuffed with any light springy material, as wool. The form thus given to the pockets throws them into an arched form 65 in the bustle, as seen in Fig. 1, where the pockets are represented as filled, and the material is secured to a waistband, C, and side tapes or bindings, D. The ends of the pockets are forced closely together before the binding D is secured in place, as seen at *d*, whereby the expansion of the filling material just outside of binding serves to hold the ribs or pockets apart to the extent of the fabric.

F designates the lacing-plates, and *f* the lacing-cord, by which the size and contour of the form may be adjusted at will. In each plate F, adjacent to its junction with the edge binding D, I arrange a stay, G, which may be of ordinary twin wire secured in the fabric of the plate by a row of stitches or by eyelets *g*. These springs serve efficiently to keep the edges from doubling or working up, as well as to support the ribs in their arched form.

The completed rib, stuffed and arched, I 85 designate by the letter B.

In details of construction modifications may be made within wide limits without departing from the principle or sacrificing the advantages of my invention.

90 The stays G may be secured to the bindings D.

By the term "arched," as applied to the ribs B, I imply that the central portion of each rib is more or less above the horizontal plane 95 of its ends, and that the ribs are at an angle with the waistband.

What I claim as new is—

1. A bustle having a series of ribs, B, of arched form, with the central portion of each 100

rib at a higher plane than either of its ends, and means for securing the same in such position to increase the capacity of the ribs to resist downward pressure of drapery, as set forth.

- 5 2. The combination, with the arched ribs, as described, consisting of stuffed curved pockets supported by a fabric, A, of side bindings, D, arranged to hold the ends of the ribs forcibly together, and by the expansibility of the filling to throw the central portions of the ribs down to the limits of the fabric, as set forth.
- 10 3. The combination, with a body, as A, having arched ribs B, and with lacing-aprons

F, of stays G, arranged in said aprons close 15 to the line of its attachment with the body, as set forth.

4. The bustle described, having the arched ribs B, with their ends held in close contact by bindings D, the lacing-aprons F, cord f, 20 and stays G, all combined and arranged to serve as set forth.

In testimony whereof I affix my signature in presence of two witnesses.

CHARLES CLARENCE CARPENTER.

Witnesses:

J. B. NONES,
S. STEINHEIMER.
